UNITED STATES PATENT OFFICE

96,827

DESIGN FOR RIBBON

John R. Fridlington, Cliffside Park, N. J.

Application December 20, 1934, Serial No. 54,524

Term of patent 14 years

To all whom it may concern:

Be it known that I, John R. Fridlington, a citizen of the United States and a resident of the Borough of Cliffside Park, in the county of Bergen and State of New Jersey, have invented a new, original, and ornamental Design for Ribbon, of which the following is a specification, reference being had to the accompanying drawing, forming part thereof.

The drawing shows a plan view of a piece of

ribbon embodying my new design, in which the ribbon is of a single color and is provided with alternate lustrous and dull longitudinal stripes outlining zones of bands or stripes of different shades, the weave of the lustrous stripes imparting a brick-like appearance.

I claim:

The ornamental design for ribbon as shown and described.

JOHN R. FRIDLINGTON.
